C. A. CAMPBELL

LIGHTING GLOBE

Filed July 3, 1924

Inventor,

Charles A. Campbell.

By

James P. Duhamel,

Attorney

UNITED STATES PATENT OFFICE.

CHARLES A. CAMPBELL, OF NEW YORK, N. Y.

DESIGN FOR A LIGHTING GLOBE.

Application filed July 3, 1924. Serial No. 10,047. Term of patent 3½ years.

To all whom it may concern:

Be it known that I, CHARLES A. CAMPBELL, a resident of New York, county of New York, and State of New York, citizen of the United States, have invented a certain new, original, and ornamental Design for Lighting Globes, of which the following is a specification, reference being had to the accompanying drawing, forming a part thereof.

The drawing is a side elevation of a lighting globe showing my new design.

The globe in contour consists of substantially the semi-spherical body portion A with the lower protuberance B and above the body portion and about the diameter is a bay or molding C substantially semi-circular and terminating in parabolas D that

terminate in moldings E E which enclose the attaching groove F.

In addition to these ornamental features the globe is supplied with alternate designs of an oval enclosing a Maltese cross and arcs having scrolled ends above and leaves below, and inverted U-shaped scrolls with knots above and balls beneath. Around the protuberance B is a circle of crescents and about the molding C is a band of lines and dots and dashes.

I claim:

The ornamental design for a lighting globe as shown and described.

In testimony whereof I hereunto affix my signature.

CHARLES A. CAMPBELL.
